UNITED STATES PATENT OFFICE.

ALBERT HENRY TIMMIS, OF HARROW, ENGLAND, ASSIGNOR TO HAMILTON & COMPANY (LONDON) LIMITED, OF LONDON, ENGLAND.

PAINT AND OTHER BRUSH.

1,372,108.

Specification of Letters Patent. Patented Mar. 22, 1921.

Application filed March 25, 1920. Serial No. 368,484.

To all whom it may concern:

Be it known that I, ALBERT HENRY TIMMIS, a citizen of the United States of America, residing at Fairmount, Harrow View, Harrow, Middlesex, England, have invented new and useful Improvements in Paint and other Brushes, of which the following is a specification.

This invention relates to paint and other brushes and it has for its object to provide improved means for the attachment of the bristles to the handle.

It is a general practice to secure the bristle knot to the handle either by means of a connecting ferrule or by cementing it into a socket in the said handle, the said socket being in some cases formed with slits and bound around with twines after the bristles have been inserted. Both these methods of attaching the bristles to the handles of brushes are, however, open to objection in practice as it is found that the connection tends to become loose with use, mainly due to the fact that the ferrule loses its grip on the handle or that the lip of the socket splits.

According to the invention I insert the bristle knot, the end of which has been dipped into a cement, such as rubber cement, through a ferrule of ductile metal, of a shape and dimensions such that it can be inserted into, and of a length such that when so inserted its end projects for a short amount from the socket.

The ferrule with the inserted bristle knot is introduced into the handle socket and the projecting end of the said ferrule is then bent outward and downward so as to be folded over the lip of the socket. This can be effectively accomplished by a taper die and the shaping operation tends to constrict the ferrule and so causes it to grip the bristles.

As will be readily understood the method of securing bristles to brush handles above described overcomes the defects inherent in the existing modes of attachment and provides a secure grip upon the bristles and a metal binding around the lip of the socket which is thus prevented from splitting.

To enable the invention to be fully under-

stood, I will describe it by reference to the accompanying drawing, in which:

Figure 1 is a sectional view of a brush made according to the invention.

Fig. 2 is a vertical section of the ferrule 55 detached.

Fig. 3 is a sectional view of the handle detached, and

Fig. 4 is a similar view to Fig. 1, but illustrating an intermediate stage in the manufacture of the brush.

a indicates the handle of the brush and *b* the socket or recess provided therein. *c* indicates the ferrule of ductile metal which is, as above described, of a shape and diameter to fit snugly in the said socket or recess *b* and of a length such that, when placed in the latter, it projects to a short extent therefrom. *d* indicates the bristle knot which is of a size to fit into the ferrule *c*. 70

In manufacturing the brush the end of the bristle knot *d* is dipped into a suitable cement, such as rubber cement, and the said knot is then passed into the ferrule *c*. The ferrule with the knot *d* in place is then inserted into the socket or recess *b* of the handle *a*, as shown in Fig. 4. Finally the projecting end of the ferrule is then bent outward and downward, say by means of a die, so as to clasp the lips of the socket, 80 this operation constricting the said ferrule and the socket lip so as to cause it to grip the bristle knot *d*, as shown in Fig. 1.

As will be evident the process of thus turning over the projecting end of the ferrule and constricting the diameter of the lip of the socket *b* imparts an undercut formation to the said socket and ferrule, whereby the bristle knot is securely held in place in the handle. Moreover, as the 90 lip of the socket is incased or bound in metal it is protected against splitting.

It is to be understood that the invention is applicable to brushes of the usual round, oval or flat shapes.

Claims.

1. The method of manufacturing paint and other brushes, which consists in applying adhesive material to the end of the bristle knot, passing the end of the bristle 100

- knot into a ferrule of ductile metal, then inserting a portion of the ferrule into a socket in the brush handle, then crimping the projecting portion of the ferrule over 5 the lip of the socket, so as to constrict the diameter of the lip of the socket and the ferrule, thereby causing the restricted lip and ferrule to grip the bristle knot and secure it within the socket.
- 10 2. In a brush, the combination with a handle provided with a socket, of a ferrule adapted to fit in said socket and of such

length as to project therefrom, said ferrule having outwardly and downwardly turned portions to engage the lip of the socket, and 15 a bristle knot, the outwardly and downwardly turned portions of the ferrule being crimped upon, restricting the diameter of, and reinforcing the lip of the socket, the said restricted lip and crimped ferrule grip- 20 ping the bristle knot and securing it within the socket.

ALBERT HENRY TIMMIS.
